US00D876507S

(12) **United States Design Patent** (10) **Patent No.:** **US D876,507 S**
(45) **Date of Patent:** **** Feb. 25, 2020**

(54) **COVER FOR A CAMERA**

(71) Applicant: **Hangzhou Hikvision Digital Technology Co., Ltd.**, Zhejiang (CN)

(72) Inventor: **Yao Liu**, Zhejiang (CN)

(73) Assignee: **Hangzhou Hikvision Digital Technology Co., Ltd.**, Zhejiang (CN)

(**) Term: **15 Years**

(21) Appl. No.: **29/642,356**

(22) Filed: **Mar. 29, 2018**

(30) **Foreign Application Priority Data**

Sep. 30, 2017 (CN) 2017 3 0474511

(51) **LOC (12) Cl.** **16-01**

(57) **CLAIM**

The ornamental design for a cover for a camera, as shown and described.

DESCRIPTION

FIG. 1 is a front view of a cover for a camera showing my new design.

FIG. 2 is a rear view thereof.

FIG. 3 is a left-side view thereof.

FIG. 4 is a right-side view thereof.

FIG. 5 is a top view thereof.

FIG. 6 is a bottom view thereof; and,

FIG. 7 is a perspective view thereof.

The broken lines depict portions of the cover for a camera in which the design is embodied that form no part of the claimed design.

1 Claim, 3 Drawing Sheets

FIG. 1

FIG. 2

FIG. 3

FIG. 4

FIG. 5

FIG. 6

FIG. 7
